THEODORE ABRAMS, OF WOODHAVEN, NEW YORK, ASSIGNOR TO STUDIO COUCH
PATENTS CO. INC., A CORPORATION OF NEW YORK

COMBINATION FURNITURE

Application filed June 16, 1932. Serial No. 617,622.

This invention relates to combination furniture, and has more particular reference to certain improvements in combined lounges and beds of the type which include two frames nested one within the other when used as a lounge and in which the frames are either disposed in side by side contiguous relation to serve as a double bed or separated from each other to serve as twin or individual beds. Furniture of this type is variously known in the trade as "twin studio divans", "bed couches" or under other similar names, which are really immaterial so far as the present invention is concerned except for the purpose of defining generally the type of furniture to which the invention relates.

Articles of furniture of this type which are now in general use and on the market have been found to be open to the objection and to possess the distinct disadvantage that they are difficult and laborious for one person to shift the two frames from the nested relation to the opened or unnested relation, as it requires either bending over and grasping of the outer frame at the center of the lower edge or grasping of the upper mattress, which tends to distort or disfigure the same. In contradistinction to this, the shifting of the frames to a nested relation is neither difficult nor laborious.

The present invention therefore broadly comprehends the conceptive idea of providing in combination furniture of this character, normally restrained or detained manually releasable interengaging means on said frames which acts, when released, to shift the frames from a nested to an unnested relation.

More particularly, the invention embodies the provision of means on one of the frames which engages with means on the other frame to place one of said means under tension when the frames are moved to nested position, together with means for holding or retaining said frames when so nested against movement to unnested position by the tension of said means until manually released.

The invention further contemplates such means which does not, when released, estab-

lish a connection between the frames which would serve as an impediment or obstruction to the complete separation of the frames for use as separate or twin beds.

The invention furthermore resides in the provision of detaining or retaining means for the purpose set forth so constructed and arranged as to permit of manual release from either end of the couch, so that the person effecting the release is so located as to be disposed out of the path of movement of the movable frame as the same is moved by the tension means to the unnested position.

As a still further object, the invention embodies an improvement of the indicated character which is comparatively simple in its construction and mode of operation, which may be inexpensively produced and installed upon or incorporated in articles of furniture of this character and which is highly efficient in its purpose.

With the above recited and other objects in view, reference is had to the following specification and accompanying drawing, in which there is illustrated a preferred embodiment of the invention, while the claims define and mark out the actual scope of the invention.

In the drawing:

Figure 1 is a plan view with parts broken away and shown in section to disclose the underlying structure and illustrating in full and broken lines the several positions of the frames.

Figure 2 is a transverse sectional view taken approximately on the line indicated at 2-2 in Figure 1.

Figure 3 is an enlarged fragmentary vertical section taken approximately on the line indicated at 3-3 in Figure 1.

Referring to the drawing by characters of reference, A and B designate generally the two frames of the combined lounge and bed or beds, and in the present instance the frame A will be referred to as the outer or movable frame and the frame B as the inner or fixed frame, although it is to be understood that this is not intended as a limitation upon the scope of the invention but is employed for the sake of clearness in describing the same.

As shown, the outer or movable frame is designed to move from the dotted line nested position covering the inner or fixed frame to the full line extended or unnested position, 5 as illustrated in Figures 1 and 2, it being understood that the outer or movable frame is larger in height, width and depth for this purpose, as is the common construction of these articles. The frame A includes an 10 upper front rail 10 and an upper rear rail 11, upper end rails 12 and depending front and rear legs 13 and 14 which are provided with castors, rollers or equivalent floor bearing elements 15 by virtue of which the frame 15 may be readily moved. The rear frame B likewise includes front and rear side rails 16 and 17, end rails 18 and depending front and rear legs 19 and 20 which are also provided with castors or equivalent floor bearing 20 elements 21. As is customary in these articles of furniture, the movable and fixed frames are respectively provided with inter-engageable elements 22 and 23 which are in the nature of reversely directed hooks or 25 equivalent means, the purpose of which is to prevent complete separation of the frames when extended or moved to an unnested position so as to locate and hold the same in contiguous relation when the frames are to 30 form a double bed when extended. The elements 22 and 23 may, however, be readily disengaged by lifting one frame slightly with reference to the other so that the frames may be independently used as separate or twin 35 beds. The foregoing is a general description of the type of article of furniture to which the invention pertains, and, as previously set forth, the movable outer frame has heretofore been moved from a nested position 40 telescopically arranged over the fixed inner frame by directly pulling the movable frame outwardly in any manner in which the user elects or can accomplish the movement.

The present invention aims to provide suitable means such as herein disclosed or its equivalent, for normally urging or shifting the frames apart to an unnested or extended position, which means, as illustrated in Figures 1 to 3, inclusive, consists of a pair of 45 coiled contractile springs 25, the outer ends of which are respectively anchored as at 26 to the front legs 19 of the inner or fixed frame B, and the inner ends of which are respectively engaged in the apertured ears 27 of an 50 abutment plate 28 to connect the springs with said plate and form an elastic element spanning spaced portions of the frame. The plate 28 is suspended and mounted for guided movement from a position adjacent the front 55 of the inner or fixed frame B, as shown in full lines in Figure 1, to a position adjacent the rear of the frame B, as illustrated in dotted lines in Figure 1. As shown, the plate 28 is provided with upstanding arms 29 which 60 are apertured and receive therethrough the

suspension and guide wires 30 which are anchored to and extend between the front and rear upper side rails 16 and 17 of the frame B. The means further includes a push or thrust bar 31 which is anchored at 32 to the front of the outer or movable frame A and which extends transversely rearward from the front of the frame A to the rear thereof, said push or thrust bar being supported adjacent its rear end by a depending leg 33 which is provided with a castor or other equivalent floor bearing element 34. From this construction and arrangement, it is apparent, assuming the frames to be in the full line position illustrated in Figures 1 and 2, that movement 70 of the frame A inwardly toward the frame B to nest the frames will cause the leg 33 of the push or thrust bar to contact and engage with the abutment plate 28, and as the frames are moved to nesting relation, the abutment 75 plate moving from its normal position adjacent the front of the frame B toward the rear of the frame B will stretch the springs 25 and place them under tension, which tension is sufficient when the frames are completely nested to shift the frames from the nested to the unnested relation, which movement due to momentum is arrested when the 80 elements 22 and 23 come into contact.

In order to provide means for detaining or locking the frames in nested relation against the action of the springs 25 when placed under tension, any suitable detent means may be employed. This detent or locking means which has been selected for the 85 purpose of the present illustration consists of a latch bolt 35 which is mounted and guided for vertical movement in a latch housing 36 and is normally projected downwardly by a spring 37, where it is disposed in the path of 90 movement of a catch terminal 38 provided at the free inner end of the push or thrust bar 31. The catch terminal is formed with an inclined cam face 39 which cams the bolt 35 upwardly against the action of the spring 37 95 when the frames are moved to fully nested condition and the bolt 35 then obviously retains and holds the frames in nested condition with the springs 25 under tension until the latch bolt 35 is moved upwardly out of engagement with the catch terminal 38. As shown, the bolt housing 36 is secured to a depending bracket 40 which is secured to the rear side rail 17 of the frame B. In order to provide means for releasing the latch bolt 35, 100 which means may be manipulated from either end of the couch, a flexible cable 41 is attached to the latch bolt 35 and is provided with branch leads 42 and 43 which are respectively trained over guide sheaves 44 and 45. The 105 opposite ends of the branch leads 42 and 43 extend through the ends of the frame B, preferably adjacent the rear side rails 17 and the terminals are provided with manipulating 110 rings or equivalent elements 46.

From the foregoing, it will thus be seen that when the frames are in the unnested or full line relation illustrated in the drawing, it is only necessary to push the frame A inwardly to a nested position with respect to the frame B, which initially causes the leg 33 to contact with and move the abutment plate 28, thereby stretching and placing the springs 25 under tension. As the catch terminal 38 engages with the latch bolt 35, the frames are automatically locked in nested relation with the springs under tension, so that immediately upon release by exerting a pull upon either of the manipulating rings 46, the frame A will move to an unnested extended position. Obviously, when so moved or ejected, the elements 22 and 23 in addition to acting as stops for limiting the opening movement of the frame A, serve to retain the frames in contiguous side by side relation whereby the frames may be used as a double bed. If it is desired to use the frames separately as individual or twin beds, the elements 22 and 23 are disengaged.

From the foregoing, it will thus be seen that an improvement in combination furniture of the indicated character has been devised which is exemplified in the preferred form of the invention as set forth, but it is to be clearly understood that no limitation is intended to the precise structural details, which may be varied in accordance with the scope of the appended claims.

What is claimed is:

1. A combination article of furniture including a pair of laterally nestable bed frames and interengageable means on said frames for shifting the same from a nested to an unnested relation comprising an elastic element extending longitudinally across one side of one frame, a rigid element on the other frame for engaging said elastic element and placing said element under tension when the frames are moved to the nested relation and manually releasable detent means for holding the frames in nested relation against the action of the tensioned elastic means.

2. In an article of furniture including a pair of nestable bed frames, means to propel one of the frames from its nested position with respect to the other frame, said means comprising an elastic element carried by one of the frames in a spanning position, means carried by the other frame for impacting said elastic element upon closing movement of the frame to produce a bight in said element and to place said element under tension, and manually releasable detent means having coacting elements on the respective frames, which elements interlock upon closure of the frames.

3. In a combination article of furniture of the character set forth including a pair of laterally nestable frames; interengageable means on said frames for shifting the same from a nested to an unnested or extended po-

sition comprising an elastic element extending longitudinally across one side of one frame and a rigid element extending transversely across the other frame for engaging said elastic element and placing the same under tension when the frames are moved to nested relation.

4. In a combination article of furniture of the character set forth including a pair of laterally nestable frames; interchangeable means on said frames for shifting the same from a nested to an unnested or extended position comprising an elastic element extending longitudinally across one side of one frame and a rigid element extending transversely across the other frame for engaging said elastic element and placing the same under tension when the frames are moved to nested relation, said elastic element comprising a pair of coiled contractile springs anchored at their outer ends to the opposite ends of the frame and an abutment plate to which the inner ends of the springs are connected and means for supporting and guiding said abutment plate for transverse movement.

5. In a combination article of furniture of the character set forth including a pair of laterally nestable frames; interengageable means on said frames for shifting the same from a nested to an unnested or extended position comprising an elastic element extending longitudinally across one side of one frame and a rigid element extending transversely across the other frame for engaging said elastic element and placing the same under tension when the frames are moved to nested relation, said elastic element comprising a pair of coiled contractile springs anchored at their outer ends to the opposite ends of the frame and an abutment plate to which the inner ends of the springs are connected and means for supporting and guiding said abutment plate for transverse movement, said transverse rigid means on the other frame consisting of a bar having a depending leg adjacent its free end for engagement with said abutment plate.

6. In a combination article of furniture of the character set forth including a pair of laterally nestable frames; interengageable means on said frames for shifting the same from a nested to an unnested or extended position comprising an elastic element extending longitudinally across one side of one frame and a rigid element extending transversely across the other frame for engaging said elastic element and placing the same under tension when the frames are moved to nested relation, said elastic element comprising a pair of coiled contractile springs anchored at their outer ends to the opposite ends of the frame and an abutment plate to which the inner ends of the springs are connected and means for supporting and guiding said abutment plate for transverse move-

- ment, said transverse rigid means on the other frame consisting of a bar having a depending leg adjacent its free end for engagement with said abutment plate and 5 means at the free end of said bar and on the other frame adapted to interengage when the frames are nested, for locking the same.
7. In a combination article of furniture of the character set forth including a pair 10 of laterally nestable frames; interengageable means on said frames for shifting the same from a nested to an unnested or extended position comprising an elastic element extending longitudinally across one side of one 15 frame and a rigid element extending transversely across the other frame for engaging said elastic element and placing the same under tension when the frames are moved to nested relation, said elastic element comprising 20 a pair of coiled contractile springs anchored at their outer ends to the opposite ends of the frame and an abutment plate to which the inner ends of the springs are connected and means for supporting and guiding 25 said abutment plate for transverse movement, said transverse rigid means on the other frame consisting of a bar having a depending leg adjacent its free end for engagement with said abutment plate, means 30 at the free end of said bar and on the other frame adapted to interengage when the frames are nested, for locking the same and means for releasing said locking means.
8. In a combination article of furniture 35 of the character set forth including a pair of laterally nestable frames; interengageable means on said frames for shifting the same from a nested to an unnested or extended position comprising an elastic element ex- 40 tending longitudinally across one side of one frame and a rigid element extending transversely across the other frame for engaging said elastic element and placing the same under tension when the frames are moved to 45 nested relation, said elastic element comprising a pair of coiled contractile springs anchored at the outer ends to the opposite ends of the frame and an abutment plate to which the inner ends of the springs are connected 50 and means for supporting and guiding said abutment plate for transverse movement, said transverse rigid means on the other frame consisting of a bar having a depending leg adjacent its free end for engagement 55 with said abutment plate, means at the free end of said bar and on the other frame adapted to interengage when the frames are nested, for locking the same and means for releasing said locking means including manipulating 60 elements located adjacent the opposite ends of the frame.

THEODORE ABRAMS.
